UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

STAIR-CARPET FASTENER.

1,299,546.

Specification of Letters Patent.

Patented Apr. 8, 1919.

Application filed October 8, 1917. Serial No. 195,249.

To all whom it may concern:

Be it known that I, JAMES H. BOYE, a citizen of the United States, residing at Chicago, in the county of Cook and State of Illinois, have invented certain new and useful Improvements in Stair-Carpet Fasteners, of which the following is a specification.

This invention relates to stair carpet fasteners of that general type employing a rod lying in the angle of the carpet between the tread and riser, and clamps that are detachably secured to the angle portion of the stairway formed by the junction of the tread and riser outside the edges of the carpet and engage the rod to hold the latter in place; although in a somewhat simpler form of my invention, the rod may be dispensed with, and the clamps alone relied upon as carpet fasteners.

The principal objects of the invention are, first, to provide a fastener wherein the rod will be so held as to prevent central springing or bulging of the same away from the carpet and insure that the rod shall lie throughout its full length in engagement with the carpet, to provide a fastener construction readily adaptable to the varying standard widths of stair carpet now in vogue; to provide a fastener which may serve satisfactorily either with or without the rod; to provide a fastener of simple construction and neat appearance, and which may be easily applied and removed.

Other objects and advantages of the invention will be apparent to those skilled in the art from a consideration of the following detail description taken in connection with the accompanying drawings, wherein,—

Figure 1 is a perspective view of a fragment of a stairway and stair carpet showing the preferred form of my improved fastener applied thereto;

Fig. 2 is a fragmentary view on an enlarged scale, looking directly into the junction of the tread and riser;

Figs. 3, 4 and 5 are cross sectional details on the corresponding lines of Fig. 2;

Fig. 6 is a longitudinal section on the line 6—6 of Fig. 5;

Fig. 7 is a view similar to Fig. 1, illustrating the use of the device without the rod;

Fig. 8 is a longitudinal section on the line 55 8—8 of Fig. 9;

Fig. 9 is a cross section on the line 9—9 of Fig. 8.

In the drawings, 10 designates the tread and 11 the riser of a stairway, and 12 designates the stair carpet designed to be secured in place on the stairway by my improved fastener. Referring first to the form of the invention illustrated in Figs. 1 to 6 inclusive, 13 designates a straight round rod 65 that overlies that portion of the carpet lying in the joint or angle formed between the tread and riser. The end portions of this rod are engaged by fastening clamps, each of which is of approximately semi-tubular 70 form in cross section and comprises a curved elbow portion 14 that lies outside the edge of the carpet and has tapered edges 15 and 16 that engage the surfaces of the tread and riser adjacent to the joint formed by these 75 parts, and a relatively long arm portion 17 that overlies the edge portion of the carpet and to a considerable extent the end portions of the rod 13, as most clearly shown in Figs. 2 and 6. The angular relation of 80 the elbow 14 and arm 17 is such that the latter does not lie parallel with the rod 13, but at a narrow angle to the latter, as clearly shown in Fig. 6, so that the arm 17 engages the rod 13 only at its free end, as 85 indicated at 18, this point being a considerable distance inwardly of the extreme end of the rod 13. The arm 17, at or adjacent to its junction with the elbow 14 is provided with a slot 19, through which is 90 passed a fastening screw 20 that enters the tread member 10, or the lower portion of the riser 11 (as the case may be) and serves to hold the clamp member securely in engagement with the rod. For ease of application and removal of the clamp, the head of the screw 20 has its opposite edges flattened, as clearly shown in Fig. 2, so that by giving the same a quarter turn, the head 95 will lie in register with the slot 19, permitting the clamp to be readily applied or removed without withdrawing the screw.

The clamp member, in the preferred form thereof herein shown, embodies two other structural characteristics which adapt it to 100 serve well the function of a stair carpet fastener without the rod 13, where a simpler and more economical fastener may be de-

sired. By reference to Fig. 2 it will be observed that the long arm 17 is tapered edge-wise from a maximum width at the elbow 14 to its free or rod-engaging end. By reference to Figs. 6 and 8 it will also be observed that the longitudinal edges of the arm 17 are not straight throughout, but are slightly beveled or tapered from a point indicated at 21 to the free end; this portion of the free edges lying at a narrow angle to the main portion of said free edges.

The advantages of these structural features will be apparent from Figs. 7 to 9 inclusive which illustrate the use of the clamp members alone as a carpet fastener. In this case the clamp members are secured in position by the same means as is shown in Figs. 1 to 6 inclusive (screws 20) and the portions of the carpet adjacent to the angle are engaged by the tapered or beveled portions of the edges of the arm 17 lying beyond the points 21; such tapered or beveled portions being designated in Figs. 8 and 9 by 22. The longitudinal tapering of the arm 17 itself effects a desirable distribution of the metal for strength purposes, and also substantially closes the joint between the fastener and the carpet, preventing the introduction of dust and dirt beneath the fastener although the actual clamping effect is done by the slightly beveled or tapered edges 22.

It is believed that the structural characteristics, mode or principle of operation, and the advantages of the invention will be readily understood by those familiar with this class of devices without further detailed description. Where the rod 13 is employed, the application of the holding pressure at points considerably inwardly of the ends of the rod holds the latter against the carpet throughout its entire length, and prevents the central bulging or springing of the rod away from the carpet, which occurs where the clamps engage the rod only at its extreme ends, as heretofore. Again, by providing for a substantial overlap of the clamps and the rod, the device, made in one size, is adaptable to the standard (22, 24 and 27 inch) widths of stair carpet now in use, with a mere variation in the extent of overlap in the different sizes. For thoroughly sweeping and cleaning the carpet and stairway the fastener is readily removable by a mere quarter turn of the screws 20, and can be removed and replaced with a negligible amount of time and labor, thereby giving to the device a sanitary character. In the form shown in Figs. 7 to 9 inclusive, the clamps engage the carpet at the same relatively advantageous points that they engage the rod, so as to prevent central bulging or springing of the carpet at the joint and hold the latter snugly against the tread and riser throughout the full width of the carpet.

It is manifest that the specific form and

details of the structure described may be modified without departing from the principle and substantial character of the device. Hence, I do not limit the invention to the exact embodiment herein selected for purposes of illustration, but reserve all such variations and modifications as fairly fall within the spirit and purview of the appended claims.

I claim:

1. In a stair carpet fastener, the combination of a rod adapted to lie in the angle of the carpet, and clamps adapted to be secured in the angle formed by the tread and riser outside the edge of the carpet and overlapping and bearing upon said rod only at points inwardly of the ends of the latter.

2. In a stair carpet fastener, the combination of a rod adapted to lie in the angle of the carpet, and clamps for said rod, each of said clamps comprising a curved portion adapted to fit and be secured in the angle formed by the tread and riser outside the edge of the carpet, and a relatively long arm portion overlapping an end of said rod and bearing at its free end only upon the latter.

3. In a stair carpet fastener, the combination of a rod adapted to lie in the angle of the carpet, and clamps for said rod, each of said clamps comprising a curved portion adapted to fit and be secured in the angle formed by the tread and riser outside the edge of the carpet and a relatively long straight arm portion overlapping an end of said rod at an angle to the latter and bearing at its free end only upon said rod.

4. In a stair carpet fastener, the combination of a round rod adapted to lie in the angle of the carpet, and clamps for said rod, each of said clamps comprising a curved portion adapted to fit and be secured in the angle formed by the tread and riser outside the edge of the carpet, and a relatively long straight arm portion of substantially semi-tubular form in cross-section overlapping an end of said rod at an angle to the latter and bearing at its free end only upon said rod.

5. In a stair carpet fastener, the combination of a rod adapted to lie in the angle of the carpet, clamps, each comprising a curved portion adapted to fit in the angle formed by the tread and riser outside the edge of the carpet and a relatively long arm portion overlapping an end of said rod and bearing at its free end only upon the latter and provided adjacent to its juncture with said curved portion with an oblong slot, and fastening screws engaging said slots and formed with oblong heads adapted to pass through said slots when turned so as to register with the latter.

6. As an article of manufacture, a stair carpet clamp of approximately semi-tubular

- form in cross-section and comprising a curved elbow portion having a V-shaped free end adapted to fit the angle formed by the tread and riser of the stairway outside the edge of the carpet and a straight arm portion longer than said elbow portion adapted to overlie the edge portion of the carpet and at its free end clamp the carpet against both the tread and riser.
- 5 7. As an article of manufacture, a stair carpet clamp of concavo-convex form in cross-section and comprising a curved elbow portion having a V-shaped free end adapted to fit the angle formed by the tread and riser of the stairway outside the edge of the carpet and a straight arm portion longer than said elbow portion adapted to overlie the edge portion of the carpet, the edges of said arm portion being longitudinally tapered or beveled for a distance inwardly of the free end of said arm portion, and said tapered or beveled portions of said edges serving to clamp the carpet against both the tread and riser.
